UNITED STATES PATENT OFFICE.

ALFRED L. SEWELL, OF EVANSTON, ILLINOIS.

CLASP AND TAG FOR ENVELOPES.

SPECIFICATION forming part of Letters Patent No. 425,053, dated April 8, 1890.

Application filed January 30, 1888. Serial No. 262,306. (No model.)

To all whom it may concern:

Be it known that I, ALFRED L. SEWELL, a citizen of the United States, residing at Evans-
ton, in the county of Cook and State of Illi-
nois, have invented a new, useful, and Im-
proved Clasp for Envelopes, of which the fol-
lowing is a specification, reference being had
to the accompanying drawings, in which—

Figure 1 is a plan view of the back of an
envelope with the clasp attached. Fig. 2 is a
detail showing the clasp detached. Fig. 3 is a
detail showing one flap of the clasp. Fig.
4 is a detail showing the connecting strap or
clamp open or unfolded. Fig. 5 is a detail
showing the wire loop for attaching the strap
or clamp to the flaps. Fig. 6 is a cross-section
on line *x x* of Fig. 2. Fig. 7 is a cross-section
on line *y y* of Fig. 1.

This invention has for its object to provide
novel, efficient, durable, and economical clasp
devices for securely closing sample and like
envelopes, while permitting them to be con-
veniently and quickly opened and reclosed
as occasion may demand.

The object of the invention is accomplished
by the features of construction and combina-
tion of devices hereinafter described and
claimed.

In the drawings, *A* indicates the envelope;
B, the clasp; *a b*, the end flaps of the envelope
A; *c c*, the side flaps of the envelope *A*; *d*, the
attaching flaps or tabs of the clasp *B*; *e*, wire
loops; *f*, the connecting fastener or clamp; *g*, a
re-enforcing strip; *h*, an eyelet.

The envelope *A* is made of paper or other
suitable material and folded in the usual
form, one flap *a* being left open for the inser-
tion of the contents, and the side flaps *c c* and
end flap *d* being gummed down as usual.

The clasp *B* is formed as follows: The flaps
or attaching-tabs *d* are made separate, and
preferably as shown in Fig. 3. The flap *a* of
the envelope may be gummed or not, as de-
sired. The tabs or flaps *d* are gummed on
one side, the loop *e* is placed in the position
indicated by the dotted lines in Fig. 3, and
the extended end of the tab or flap is moist-
ened and folded back so as to hold the loop
in place. It is then ready for attachment to
the envelope. The form of the tabs *d* is not
material. The form shown gives a neat ap-

pearance; but it is evident that various forms
may be used. A tab with its loop in place
may be attached to the flap *a*, but usually it
will be more convenient to connect them to-
gether, as shown in Figs. 1 and 6, and apply
them to the envelope after it is filled, so that
the clasp will accommodate itself to the filling
or contents. The clasp-plate *f* is best made
of thin tin or taggars metal in the form shown
at Fig. 4, and it is usually attached to one or
both of the loops *e* and bent at or about the
dotted lines there shown. When attached to
one flap *d* only, the opposite end will be bent
nearly to a right angle, so as to receive and
hold the other loop, and when the second loop
e is in place it is then bent to place, as shown
in Figs. 1, 2, and 6.

When the envelope is to be opened for in-
spection, or otherwise, the uncovered end of
the clamp or holding-plate *f* is turned up,
when the envelope is readily opened without
injury to the envelope or its contents, and
may then be readily reclosed, as the plate may
be bent many times without destroying it.

The tabs *d* and clamp *B* may be used on
any form of envelope, as they are equally
efficient with envelopes opening at the side,
and are therefore separately useful as en-
velope attachments.

A cheap form of envelope for special uses
may be made by attaching the loops *e* to one
or both of the opposite flaps of the envelope
and connecting them by the clamp *f* or by its
equivalent, made of wire.

It is desirable in many cases to use a ship-
ping or direction tag instead of a direct mark-
ing on the envelope or package; but it is dif-
ficult to so attach such direction-tag to paper
that it will be certain to remain, and to obvi-
ate this difficulty I apply a thin strip of metal
g to the interior of the envelope at one end
and hold it in place by an eyelet *h*, which
fastens the strip *g* to the paper and furnishes
a hole or opening for a direction-tag. By this
arrangement I furnish a wide bearing for the
strip *g*, which enables it to resist strain and
prevents the tearing of the envelope.

What I claim as new, and desire to secure
by Letters Patent, is—

1. A clasp for closing envelopes, comprising
an adhesive tag carrying a wire loop and

adapted to be cemented to an ordinary envelope, and an adhesive attaching-tag, carrying a thin sheet-metal clasp-plate folded longitudinally upon itself and having one folded 5 part adapted to enter the loop of the adhesive tag and be compressed, substantially as described.

2. A clasp for closing envelopes, consisting of two adhesive tags adapted to be cemented 10 to an ordinary envelope and each having at

one edge a wire loop, and a thin metal clasp-plate pivoted to one of said loops and folded longitudinally upon itself, engaging both wire loops and having one folded part adapted to be turned up and down, substantially as described. 15

ALFRED L. SEWELL.
